ABSTRACT

Hair dyeing processes and compositions containing α -cyano-methanesulfonamido-nitrobenzene compounds having the formula

where Y represents hydrogen, chlorine, bromine or an alkoxy having 1 to 4 carbon atoms and Z represents NH₂ or OH, and wherein the processes of dyeing hair use these compounds directly or in combination with couplers for oxidation dyeing.

**HAIR DYEING PROCESS AND COMPOSITION
CONTAINING
 α -CYANO-METHANESULFONAMIDO-
NITROBENZENE DERIVATIVES**

OBJECTS OF THE INVENTION

An object of the present invention is the development of an α -cyano-methanesulfonamido-nitrobenzene compound having the formula

wherein Y is a member selected from the group consisting of hydrogen, chloro, bromo, and alkoxy having 1 to 4 carbon atoms, and Z is a member selected from the group consisting of amino and hydroxyl.

Another object of the invention is the development of an aqueous preparation for the direct dyeing of human hair consisting essentially of (1) from 0.1% to 5% by weight of the above α -cyano-methanesulfonamido-nitrobenzene compounds; (2) from 0% to 30% by weight of a surfactant; (3) from 0% to 25% by weight of a thickener; and (4) from 40% to 99.9% by weight of water.

A further object of the invention is the development of an aqueous preparation for the dyeing of human hair consisting essentially of (1) from 0.2% to 5% by weight of an oxidation dyestuff combination of a developer component, and a coupling component in substantially equimolar amounts, said coupling component consisting essentially of the above α -cyano-methanesulfonamido-nitrobenzene compounds; (2) from 0% to 30% by weight of a surfactant; (3) from 0 to 25% by weight of a thickener; and (4) from 40% to 99.8% by weight of water.

A yet further object of the invention is the development of a process for dyeing human hair consisting essentially of applying to said hair at temperatures ranging from about 15.0° to 40°C for a time sufficient to effect dyeing, an effective amount of either of the above aqueous preparations.

These and other objects of the invention will become more apparent as the description thereof proceeds.

DESCRIPTION OF THE INVENTION

The present invention provides novel α -cyanomethanesulfonamido-nitrobenzene compounds having the formula

wherein Y is a member selected from the group consisting of hydrogen, chloro, bromo, and alkoxy having 1 to 4 carbon atoms, and Z is a member selected from the group consisting of amino and hydroxyl.

- 5 Examples of compounds of the described type are:
2-amino-3-(α -cyano-methanesulfonamido)-1-nitrobenzene,
2-amino-4-(α -cyano-methanesulfonamido)-1-nitrobenzene,
10 1-amino-4-(α -cyano-methanesulfonamido)-2-nitrobenzene,
2-amino-4-chloro-1-(α -cyano-methanesulfonamido)-3-nitrobenzene,
15 1-amino-5-(α -cyano-methanesulfonamido)-4-methoxy-2-nitrobenzene,
2-amino-3-chloro-4-(α -cyano-methanesulfonamido)-1-nitrobenzene,
1-amino-3-(α -cyano-methanesulfonamido)-2-nitrobenzene,
20 1-amino-2-(α -cyano-methanesulfonamido)-4-nitrobenzene,
2-amino-1-(α -cyano-methanesulfonamido)-4-nitrobenzene,
1-amino-5-bromo-2-(α -cyano-methanesulfonamido)-4-nitrobenzene,
1-amino-2-(α -cyano-methanesulfonamido)-3-nitrobenzene,
25 1-amino-3-(α -cyano-methanesulfonamido)-5-nitrobenzene,
1-amino-2-chloro-3-(α -cyano-methanesulfonamido)-5-nitrobenzene,
1-amino-2-butoxy-4-(α -cyano-methanesulfonamido)-5-nitrobenzene,
40 4-amino-2-(α -cyano-methanesulfonamido)-1-nitrobenzene,
2-amino-1-ethoxy-4-(α -cyano-methanesulfonamido)-5-nitrobenzene,
2-(α -cyano-methanesulfonamido)-4-nitrophenol,
2-(α -cyano-methanesulfonamido)-6-nitrophenol
4-chloro-2-(α -cyano-methanesulfonamido)-6-nitrophenol,
2-(α -cyano-methanesulfonamido)-3-methoxy-6-nitrophenol,
6-chloro-2-(α -cyano-methanesulfonamido)-4-nitrophenol,
2-(α -cyano-methanesulfonamido)-5-nitrophenol,
45 4-bromo-5-(α -cyano-methanesulfonamido)-2-nitrophenol,
4-(α -cyano-methanesulfonamido)-2-nitrophenol,
3-(α -cyano-methanesulfonamido)-2-nitrophenol,
2-(α -cyano-methanesulfonamido)-5-nitrophenol,
2-(α -cyano-methanesulfonamido)-3-methoxy-5-nitrophenol,
50 5-chloro-2-(α -cyano-methanesulfonamido)-4-nitrophenol,
2-(α -cyano-methanesulfonamido)-3-nitrophenol,
5-butoxy-2-(α -cyano-methanesulfonamido)-3-nitrophenol,
3-(α -cyano-methanesulfonamido)-5-nitrophenol,
60 2-bromo-4-(α -cyano-methanesulfonamido)-3-nitrophenol,
2-ethoxy-5-(α -cyano-methanesulfonamido)-4-nitrophenol.

65 The compounds in accordance with the invention may be produced by reacting the corresponding nitro-amino-phenols or diamino-nitro-benzenes, substituted if required, with the stoichiometric quantity of chloro-

sulfonyl acetonitrile required for the monosubstitution of an amino group. Advantageously, reaction is effected in the presence of a solvent such as aliphatic hydrocarbons, benzene, chlorobenzene, tetrahydrofuran, in such a manner that the chlorosulfonyl acetonitrile dissolved in the particular solvent is added to the nitro-amino-phenols or diamino-nitrobenzenes drop by drop while cooling with ice. After the said substances have been added, the reaction mixture is maintained for a few hours at room temperature under agitation and is subsequently poured into water and the reaction product, obtained in the form of an oil or in solid form, is separated. The α -cyano-methanesulfonamido-nitrobenzene reaction products can be purified by recrystallization from ethanol.

The compounds in accordance with the invention are valuable hair dyes. They may be used as direct dyes which produce yellows of various tints. Compared with the starting substances used for their production, which are known as direct dyestuffs, they are characterized by better absorption and fastness properties, and also provide widely differing tints.

Furthermore, the compounds in accordance with the invention can be used as yellow couplers in oxidation dyes in combination with conventional developer substances, and the color tints obtainable can be varied by means of the developer components, and the intensity of the oxidation can be varied through various tints of yellow to brown.

Consequently, a further object of the invention is the use of compounds of the general formula

in which Y represents hydrogen, chlorine, bromine, or an alkoxy group having 1 to 4 carbon atoms, and Z represents an NH₂- or OH-group in preparations for dyeing hair.

In another aspect, therefore, the invention provides an aqueous preparation for the direct dyeing of human hair consisting essentially of (1) from 0.1% to 5% by weight of the above α -cyano-methanesulfonamido-nitrobenzene compounds; (2) from 0% to 30%, preferably 0.5% to 30%, by weight of a surfactant; (3) from 0% to 25%, preferably 0.1% to 25%, by weight of a thickener; and (4) from 40% to 99.9%, preferably 40% to 99.3%, by weight of water; as well as an aqueous preparation for the dyeing of human hair consisting essentially of (1) from 0.2% to 5% by weight of an oxidation dyestuff combination of a developer component and a coupling component in substantially equimolar amounts, said coupling component consisting essentially of the above α -cyano-methanesulfonamido-nitrobenzene compounds; (2) from 0% to 30%, preferably 0.5% to 30%, by weight of a surfactant; (3) from 0 to 25%, preferably 0.1% to 25%, by weight of a thickener; and (4) from 40% to 99.8%, preferably 40% to 99.3%, by weight of water.

Either of the above preparations can be used in the process for dyeing human hair consisting essentially of applying to said hair at temperatures ranging from about 15° to 40°C for a time sufficient to effect dyeing, an effective amount of either of the above aqueous preparations.

A particular embodiment of this subject of the invention relates to the use of compounds of the above-mentioned formulas in combination with conventional developer substances in preparation for the oxidative dyeing of hair.

In this instance, suitable developer substances are the compounds which are normally used for this purpose. The most important examples are primary aromatic amines having a further functional group in the para-position, or else a 4-aminopyrazolone.

Preferred 4-aminopyrazolones are compounds of the generic formula

wherein R₃ and R₄ are hydrogen or an organic radical having 1 to 10 carbon atoms.

The organic radical R₃ can be an alkyl having 1 to 10 carbon atoms, an aryl, such as phenyl, hydroxyphenyl, sulfonylphenyl, sulfonamidophenyl, aminophenyl, lower alkylolphenyl, lower alkylphenyl, lower alkylaminophenyl and di-lower alkylaminophenyl where the alkyls and alkylols have 1 to 4 carbon atoms, or a heterocyclic radical, such as the pyridyl. Functional groups may be present, particularly on the aryl, as indicated above, such as OH, NH₂, NHCH₃, N(CH₃)₂ or halogen atoms, i.e., fluorine, iodine, bromine, and particularly chlorine. Furthermore, the following groups may be present as organic radicals: COOH, COOR', CONH₂, CONHR', CONR'R'', wherein R' and R'' are alkyl or hydroxyalkyl having 1 to 4 carbon atoms.

The organic radical R₄ can be an alkyl having 1 to 10 carbons, an aryl, such as those mentioned above for R₃, or a heterocyclic radical, such as the pyridyl. Functional groups may be present. Particularly, hydrocarbon radicals having 1 to 10 carbons are applicable containing as functional groups OH, NH₂, COOH, CONH₂, SO₃H and SO₂NH₂.

As aromatic radical, a phenyl is especially applicable. It may be substituted with alkyl or hydroxyalkyl groups having 1 to 4 carbons or other substituents, such as halogen, preferably Cl, NH₂, OH, COOH, CONH₂, CONHR', CONR'R'', SO₃H and SO₂NH₂.

It frequently is opportune to employ the 4-aminopyrazolone in the form of their water-soluble acid addition salts, such as the hydrochloride, sulfate or oxalate, because the resistance to atmospheric air is increased.

4-Aminopyrazolones which are suitable as developers in the process of the invention are as follows:

- 1-ethyl-4-aminopyrazolone
- 1-n-hexyl-4-aminopyrazolone
- 1-n-decyl-4-aminopyrazolone
- 1-phenyl-4-aminopyrazolone
- 1-(p-hydroxyphenyl)-4-aminopyrazolone

1-(p-sulfonylphenyl)-4-aminopyrazolone
 3-methyl-4-aminopyrazolone
 3-i-propyl-4-aminopyrazolone
 3-n-octyl-4-aminopyrazolone
 3-phenyl-4-aminopyrazolone
 3-(p-ethylphenyl)-4-aminopyrazolone
 3-(p-aminophenyl)-4-aminopyrazolone
 3-(p-dimethylaminophenyl)-4-aminopyrazolone
 3-(m-chlorophenyl)-4-aminopyrazolone
 3-(4-pyridyl)-4-aminopyrazolone
 1-methyl-3-phenyl-4-aminopyrazolone
 1-ethyl-3-(o-hydroxyphenyl)-4-aminopyrazolone
 1-n-decyl-3-(p-methylaminophenyl)-4-aminopyrazolone
 1-phenyl-3-n-butyl-4-aminopyrazolone
 1-(p-sulfonamidophenyl)-3-n-octyl-4-aminopyrazolone
 1-(p-sulfonamidophenyl)-3-phenyl-4-aminopyrazolone
 1-(p-ethylphenyl)-3-phenyl-4-aminopyrazolone
 1-(p-beta-hydroxyethylphenyl)-3-phenyl-4-aminopyrazolone
 1-(p-hydroxyphenyl)-3-n-octyl-4-aminopyrazolone
 1-(p-hydroxyphenyl)-3-n-octyl-4-aminopyrazolone
 1-(p-carboxyphenyl)-3-n-octyl-4-aminopyrazolone
 1-(p-carbamidophenyl)-3-n-octyl-4-aminopyrazolone
 4-aminopyrazolone-3-carboxylic acid
 4-aminopyrazolone-3-carboxylic acid-ethyl ester
 4-aminopyrazolone-3-carboxylic acid-n-butyl ester
 4-aminopyrazolone-3-carboxylic acid-methylamide
 4-aminopyrazolone-3-carboxylic acid-hydroxymethylamide
 4-aminopyrazolone-3-carboxylic acid-di-n-butylamide
 4-aminopyrazolone-3-carboxylic acid-ethyl-beta-hydroxyethylamide
 1-methyl-4-aminopyrazolone-3-carboxylic acid-ethyl ester
 1-methyl-4-aminopyrazolone-3-carboxylic acid-n-propylamide
 1-methyl-4-aminopyrazolone-3-carboxylic acid-beta-hydroxypropylamide
 1-ethyl-4-aminopyrazolone-3-carboxylic acid-methyl ester
 1-ethyl-4-aminopyrazolone-3-carboxylic acid-amide
 1-n-aminopyrazolone-3-carboxylic acid-beta-hydroxybutylamide
 1-i-propyl-4-aminopyrazolone-3-carboxylic acid-beta-hydroxyethylamide
 1-n-butyl-4-aminopyrazolone-3-carboxylic acid-methyl ester
 1-n-hexyl-4-aminopyrazolone-3-carboxylic acid-ethyl ester
 1-n-heptyl-4-aminopyrazolone-3-carboxylic acid
 1-n-decyl-4-aminopyrazolone-3-carboxylic acid-di-n-propylamide
 1-n-decyl-4-aminopyrazolone-3-carboxylic acid-beta-hydroxyethyl ester
 1-phenyl-4-aminopyrazolone-3-carboxylic acid
 1-phenyl-4-aminopyrazolone-3-carboxylic acid-ethyl ester
 1-phenyl-4-aminopyrazolone-3-carboxylic acid-beta-hydroxyethyl ester
 1-phenyl-4-aminopyrazolone-3-carboxylic acid-amide

1-phenyl-4-aminopyrazolone-3-carboxylic acid-ethylamide
 1-phenyl-4-aminopyrazolone-3-carboxylic acid-beta-hydroxyethylamide
 1-phenyl-4-aminopyrazolone-3-carboxylic acid-dimethylamide
 1-(p-i-propylphenyl)-4-aminopyrazolone-3-carboxylic acid
 1-(p-hydroxyphenyl)-4-aminopyrazolone-3-carboxylic acid-ethyl ester
 1-(p-aminophenyl)-4-aminopyrazolone-3-carboxylic acid-amide
 1-(o-carboxyphenyl)-4-aminopyrazolone-3-carboxylic acid-ethyl ester
 1-(p-sulfonylphenyl)-4-aminopyrazolone-3-carboxylic acid-ethyl ester
 1-(p-sulfonamidophenyl)-4-aminopyrazolone-3-carboxylic acid-ethyl ester
 1-(2-pyridyl)-4-aminopyrazolone-3-carboxylic acid-diethylamide

These compounds may be used as such or in the form of their water-soluble acid addition salts.

Suitable aromatic bi- and polyfunctional amines having at least one primary amino group and another functional group in para-position are, e.g., p-phenylenediamine, p-toluylenediamine, p-diaminoanisole, p-methylaminoaniline, p-ethylaminoaniline, p-aminodiphenylamine, p-dimethylaminoaniline, p-diethylaminoaniline, p-di-beta-hydroxyethylaminoaniline, p-aminophenol, p-diaminoanisole, or compounds of the kind named which additionally contain one or more functional groups such as OH, NH₂, NHR', NR'R'', where R' and R'' again are lower alkyls or hydroxyalkyls having 1 to 4 carbon atoms.

Preferably, these aromatic bi- and polyfunctional amines have the formula

wherein Y is a member selected from the group consisting of OH, NH₂, NHR', NR'R'', and NHC₆H₅ and Z is a member selected from the group consisting of H, R', Y and OR', where again R' and R'' are alkyls or hydroxyalkyls having 1 to 4 carbon atoms.

Further suitable developers include diamino pyridine and its derivatives, for example 2,5-diamino-pyridine, and heterocyclic hydrazone derivatives, for example pyridone hydrazones such as 1-ethyl-pyridone-2-hydrazone.

The coupling components according to the invention are suitably used in substantially equimolar quantities with respect to the developers used. However, it is also possible to employ the coupling component in a certain excess over the stoichiometric amount or in a certain lesser quantity than the stoichiometric amount. Both the coupling components and the developers may be mixtures of compounds of the above-mentioned kind.

The oxidative coupling, that is, the development of the dyeing, may also be effected according to known

procedures such as by the oxygen of the air. However, chemical oxidizing agents are suitably used, especially hydrogen peroxide or its adducts with urea, melamine and sodium borate, as well as mixtures of such hydrogen peroxide adducts with potassium peroxydisulfate.

The compounds according to the invention may be present in the form of aqueous preparations, such as solutions or emulsions. Such preparations should contain the direct dye or the dyestuffs combination of coupling component and developer component in amounts of from 0.1% to 5% by weight, preferably 0.1% to 2% by weight.

The compounds according to the invention may be applied in the form of creams or emulsions. For this purpose the direct dyes, or mixtures of oxidative dyestuffs combinations of developers and couplers may be mixed with the ingredients usually present in such preparations. Such ingredients include any anionic or non-ionic wetting agents or detergents such as for example, alkylbenzenesulfonates, fatty alcohol sulfates, higher alkylsulfonates, higher fatty acid ethanolamides, or ethylene oxide adducts on higher fatty acids, higher fatty alcohols or alkylphenols. Further, such preparations may contain thickeners, as for example, methylcellulose, starch and also higher fatty alcohols, paraffin oil and fatty acids, as well as perfume oils or hair treatment agents, for example pantothenic acid and cholesterol.

The additives are utilized in the amounts effective for this purpose. An effective amount of a wetting agent or surfactant added is especially from 0.5% to 30% by weight; and an effective amount of a thickening agent added is from 0.1% to 25% by weight, calculated in each case on the total composition. The concentration of the direct dye or the dyestuffs combinations in such cream or emulsion preparations is from 0.1% to 5% by weight, preferably 0.2% to 2%, based upon the total composition, depending on the purpose for which the agent is to be used. The application of the direct dye or dyestuffs combinations may be effected at temperatures between 15°C and 40°C preferably room temperature, in weakly acid, neutral or preferably alkaline medium.

The dyeings obtained have the advantages of a good light fastness, a good washing fastness and a good fastness to rubbing. A special advantage of the hair dyes according to the invention is that they may be used both in direct dyeing and as coupling components in oxidation dyestuffs to obtain yellow colorations.

The following examples are merely illustrative of the present invention without being deemed limitative in any manner thereof.

EXAMPLE 1

1-amino-b

2-(α -cyano-methanesulfonamido)-4-nitro-benzene

A solution of 14 gm (0.1 mol) of chlorosulfonyl acetonitrile in 50 ml of absolute tetrahydrofuran was slowly added drop by drop, under ice cooling, to a solution of 15.3 gm (0.1 mol) of 1,2-diamino-4-nitrobenzene in 200 ml of absolute tetrahydrofuran. The resultant mixture was subsequently agitated for 6 hours at room temperature. The mixture was then filtered and the filtrate was poured into water, whereby an oil was precipitated which was separated from the aqueous phase. This oil solidified to a crystal paste after a period of time. The paste was filtered off and re-crystallized three times from ethanol.

Melting point: 185° to 187°C

Analysis. Molecular Weight calculated for C₈H₈N₄O₄S.

Calculated: C 37.50%; H 3.12%; N 21.88%.

Found: C 37.72%; H 2.86%; N 22.07%.

EXAMPLE 2

4-amino-2-(α -cyano-methanesulfonamido)-1-nitrobenzene

15.3 gm (0.1 mol) of 1,3-diamino-4-nitro-benzene dissolved in 100 ml of absolute tetrahydrofuran, and 14 gm (0.1 mol) of chlorosulfonyl acetonitrile dissolved in 50 ml of absolute tetrahydrofuran were reacted in the manner described in Example 1. The precipitate was recrystallized twice from ethanol.

Melting point: 216° to 217°C.

Analysis. Molecular weight calculated for C₈H₈N₄O₄S.

Calculated: C 37.50%; H 3.12%; N 21.88%.

Found: C 37.47%; H 2.82%; N 22.32%.

EXAMPLE 3

1-amino-4-(α -cyano-methanesulfonamido)-2-nitrobenzene

15.3 gm (0.1 mol) of 1,4-diamino-2-nitro-benzene dissolved in 200 ml of absolute tetrahydrofuran, and 14 gm (0.1 mol) of chlorosulfonyl acetonitrile dissolved in 50 ml of absolute tetrahydrofuran were reacted in the manner described in Example 1. The reaction product was recrystallized from ethanol. The precipitate filtered off was washed with a little ether and was subsequently recrystallized again from water.

Melting point: 157° to 162°C.

Analysis. Molecular weight calculated for C₈H₈N₄O₄S.

Calculated: C 37.50%; H 3.12%; N 21.88%.

Found: C 37.51%; H 2.79%; N 22.07%.

EXAMPLE 4

4-chloro-2-(α -cyano-methanesulfonamido)-6-nitrophenol

18.8 gm (0.1 mol) of 2-amino-4-chloro-6-nitrophenol suspended in 100 ml of absolute tetrahydrofuran, and 14.0 gm (0.1 mol) of chlorosulfonyl acetonitrile dissolved in 50 ml absolute tetrahydrofuran, were reacted in the same manner as described in Example 1. The precipitate was recrystallized twice from ethanol.

Melting point: 174° to 177°C

Analysis. Molecular weight calculated for C₈H₈N₄O₅SCl.

Calculated: C 32.93%; H 2.19%; H 14.41%.

Found: C 33.51%; H 2.06%; N 14.53%.

EXAMPLE 5

6-chloro-2-(α -cyano-methanesulfonamido)-4-nitrophenol

18.8 gm (0.1 mol) of 2-amino-6-chloro-4-nitrophenol suspended in 100 ml of absolute tetrahydrofuran, and 14.0 gm (0.1 mol) of chlorosulfonyl acetonitrile dissolved in 50 ml of absolute tetrahydrofuran, were reacted in the same manner as described in Exam-

ple 1. The precipitate was recrystallized twice from ethanol.

Melting point: 182° to 184°C.

Analysis. Molecular weight calculated for C₈H₆N₃O₅SCl.

Calculated: C 32.93%; H 2.19%; S 10.94%.

Found: C 33.08%; H 1.72%; S 10.60%.

EXAMPLE 6

2-(α -cyano-methanesulfonamido)-4-nitro-phenol

15.4 gm (0.1 mol) of 2-amino-4-nitro-phenol dissolved in 100 ml of absolute tetrahydrofuran, and 14.0 gm (0.1 mol) of chlorosulfonyl acetonitrile dissolved in 50 ml of absolute tetrahydrofuran, were reacted in the same manner as described in Example 1. The reaction product was recrystallized twice from ethanol and once from water.

Melting point: 166° to 168°C.

Analysis. Molecular weight calculated for C₈H₇N₃O₅S.

Calculated: C 37.36%; H 2.74%; N 16.34%.

Found: C 37.11%; H 2.62%; N 16.43%.

EXAMPLE 7

4-(α -cyano-methanesulfonamido)-2-nitro-phenol

15.4 gm (1.0 mol) of 4-amino-2-nitro-phenol dissolved in 100 ml of absolute tetrahydrofuran, and 14.0 gm (0.1 mol) of chlorosulfonyl acetonitrile dissolved in 50 ml of absolute tetrahydrofuran, were reacted in the same manner as described in Example 1. The precipitate was recrystallized from ethanol.

Melting point: 150° to 155°C

Analysis. Molecular weight calculated for C₈H₇N₃O₅S.

Calculated: C 37.36%; H 2.74%; N 16.34%.

Found: C 37.71%; H 2.74%; N 16.29%.

EXAMPLE 8

2 parts by weight of 1-amino-2-(α -cyano-methanesulfonamido)-4-nitro-benzene were incorporated in a cream base of the composition:

10 parts by weight of fatty alcohols C₁₆ to C₁₈,

10 parts by weight of fatty alcohol sulfate (commercial mixture C₁₆ to C₁₈),

75 parts by weight of water.

and the pH value of the mixture was adjusted to 9.5 by adding ammonia. This emulsion was made up to 100 parts by weight with water. The dyeing cream thus obtained was applied to human hair which has turned grey naturally, and was allowed to act for 30 minutes at room temperature. The hair was subsequently washed and dried. The result was hair which had been dyed a deep yellow color.

EXAMPLES 9 to 14

Using the same procedure as stated in Example 8, but with the use of the dye components in Examples 2 to

7, listed in the following Table, the hair colors given in the same line were obtained.

Ex. No.	Dye component	Hair Color obtained
9	4-amino-2-(α -cyano-methanesulfonamido)-1-nitro-benzene	olive yellow
10	1-amino-4-(α -cyano-methanesulfonamido)-2-nitro-benzene	topaz-yellow
11	4-chloro-2-(α -cyano-methanesulfonamido)-6-nitro-phenol	pompeian yellow
12	6-chloro-2-(α -cyano-methanesulfonamido)-4-nitro-phenol	honey yellow
13	2-(α -cyano-methanesulfonamido)-4-nitro-phenol	olive yellow
14	4-(α -cyano-methanesulfonamido)-2-nitro-phenol	ivory

EXAMPLE 15

Equimolar quantities of 4-amino-1-phenyl-3-carbamoyl-pyrazolone-5 acting as a developer component, and 1-amino-2-(α -cyano-methanesulfonamido)-4-nitro-benzene acting as a coupler component, were emulsified in a cream base as described in Example 8. The molar concentrations are so calculated that, assuming 100% reaction upon the subsequent oxidative coupling reaction, 2 gm of dye are present in 100 gm of cream (corresponding to a 2% concentration of dye).

The emulsion was adjusted to a pH value of 9.5 by adding ammonia and was subsequently made up to 100 parts by weight with water. The dyeing cream thus obtained dyed human hair mustard brown to yellowish brown within 30 minutes by virtue of the action of the atmospheric oxygen or a 1% or 9% solution of hydrogen peroxide. The various tints of color were obtained in accordance with the oxidation agents used (or their different concentrations).

EXAMPLES 16 to 52

40 Following the same procedure as in Example 15, but with the use of the developers and couplers given in the following Table as dye components (a) and (b), human hair which had turned grey naturally was dyed and the colors given in the last column were obtained (with atmospheric oxygen and a 1% and a 9% H₂O₂ solution). The dye components were used in equimolar quantities. The total quantity of the dye to be formed was 2 gm in 100 gm of the cream base in each case, and the reaction time was 30 minutes at room temperature.

45 50 The developer components under a are abbreviated in the Table as follows:

4-amino-1-phenyl-3-carbamoyl-pyrazolone-5 = A
4-amino-1-phenyl-3-ethoxycarbonyl-pyrazolone-5 = B

4-amino-1H-3-ethoxycarbonyl-pyrazolone-5 = C

p-toluylene diamine = D

1-methyl-pyridone-2-hydrazone = E

1-methyl-quinolone-4-hydrazone = F

The preceding specific embodiments are illustrative of the practice of the invention. It is to be understood, however, that other expedients known to those skilled in the art, or disclosed herein, may be employed without departing from the spirit of the invention or the scope of the appended claims.

I claim:

1. An aqueous preparation for the direct dyeing of human hair consisting essentially of (1) from 0.1% to 5% by weight of an α -cyano-methanesulfonamido-nitrobenzene compound having the formula

wherein Y is a member selected from the group consisting of hydrogen, chloro, bromo and alkoxy having 1 to 4 carbon atoms, and Z is a member selected from the

group consisting of amino and hydroxyl; (2) from 0% to 30% by weight of a surfactant selected from the group consisting of an anionic wetting agent and a non-ionic wetting agent; (3) from 0% to 25% by weight of a thickener; and (4) from 40% to 99.9% by weight of water.

2. The aqueous preparation of claim 1, wherein said α -cyano-methanesulfonamido-nitrobenzene compound is selected from the group consisting of 1-amino-2-(α -cyano-methanesulfonamido)-4-nitro-benzene, 4-amino-2-(α -cyano-methanesulfonamido)-1-nitro-benzene, 1-amino-4-(α -cyano-methanesulfonamido)-2-nitro-benzene, 4-chloro-2-(α -cyano-methanesulfonamido)-6-nitro-phenol, 6-chloro-2-(α -cyano-methanesulfonamido)-4-nitro-phenol, 2-(α -cyano-methanesulfonamido)-4-nitro-phenol, and 4-(α -cyano-methanesulfonamido)-2-nitro-phenol.

3. A process for direct dyeing human hair consisting essentially of applying to said hair at temperatures ranging from about 15°C to 40°C for a time sufficient to effect dyeing, an effective amount of the aqueous preparations of claim 1.

4. An aqueous preparation for the dyeing of human hair consisting essentially of (1) from 0.2% to 5% by

weight of an oxidation dyestuff combination of a developer component and a coupling component in substantially equimolar amounts, said coupling component consisting essentially of an α -cyano-methanesulfonamido-nitrobenzene compound having the formula

wherein Y is a member selected from the group consisting of hydrogen, chloro, bromo and alkoxy having 1 to 4 carbon atoms, and Z is a member selected from the group consisting of amino and hydroxyl; (2) from 0% to 30% by weight of a surfactant selected from the group consisting of an anionic wetting agent and a non-ionic wetting agent; (3) from 0 to 25% by weight of a thickener; and (4) from 40% to 99.8% by weight of water.

5. The aqueous preparation of claim 4, wherein said α -cyano-methanesulfonamido-nitrobenzene compound is selected from the group consisting of 1-amino-2-(α -cyano-methanesulfonamido)-4-nitro-benzene, 4 amin-

o-2-(α -cyano-methanesulfonamido)-1-nitro-benzene, 1-amino-4-(α -cyano-methanesulfonamido)-2-nitro-benzene, 4-chloro-2-(α -cyano-methanesulfonamido)-6-nitro-phenol, 6-chloro-2-(α -cyano-methanesulfonamido)-4-nitro-phenol, 2-(α -cyano-methanesulfonamido)-4-nitro-phenol, and 4-(α -cyano-methanesulfonamido)-2-nitro-phenol.

6. The aqueous preparation of claim 4, wherein said developer component is selected from the group consisting of a 4-amino-pyrazolone, a water-soluble acid addition salt of said 4-amino-pyrazolone, an aromatic amine having at least one primary amino group and another functional group in the para-position, a diamino-pyridine and a pyridone hydrazone.

15 7. The aqueous preparation of claim 4, wherein said developer component is selected from the group consisting of 4-amino-1-phenyl-3-carbamoyl-pyrazolone-5, 4-amino-1-phenyl-3-ethoxycarbonyl-pyrazolone-5, 4-amino-1H-3-ethoxycarbonyl-pyrazolone-5, p-tolylene 20 diamine, 1-methyl-pyridone-2-hydrazone and 1-methyl-quinolone-4-hydrazone.

8. A process for dyeing human hair consisting essentially of applying to said hair at temperatures ranging from about 15° to 40°C for a time sufficient to effect 25 dyeing, an effective amount of the aqueous preparation of claim 4.
